CLAIM

The ornamental design for animal cage, as shown and described.

DESCRIPTION

FIG. 1 is a perspective view of a first embodiment of an animal cage showing a new design;

FIG. 2 is another perspective view thereof;

FIG. 3 is a top view thereof;

FIG. 4 is a bottom view thereof;

FIG. 5 is a front view thereof;

FIG. 6 is a back view thereof;

FIG. 7 is a left side view thereof;

FIG. 8 is a right side view thereof;

FIG. 9 is a perspective view of a second embodiment of an animal cage showing another new design;

FIG. 10 is another perspective view thereof;

FIG. 11 is a top view thereof;

FIG. 12 is a bottom view thereof;

FIG. 13 is a front view thereof;

FIG. 14 is a back view thereof;

FIG. 15 is a left side view thereof;

FIG. 16 is a right side view thereof;

FIG. 17 is a perspective view of a third embodiment of an animal cage showing another new design;

FIG. 18 is another perspective view thereof;

FIG. 19 is a top view thereof;

FIG. 20 is a bottom view thereof;

FIG. 21 is a front view thereof;

FIG. 22 is a back view thereof;

FIG. 23 is a left side view thereof;

FIG. 24 is a right side view thereof;

FIG. 25 is a perspective view of a fourth embodiment of an animal cage showing another new design;

FIG. 26 is another perspective view thereof;

FIG. 27 is a front view thereof;

FIG. 28 is a back view thereof;

FIG. 29 is a top view thereof;

FIG. 30 is a bottom view thereof;

FIG. 31 is a left side view thereof; and,

FIG. 32 is a right side view thereof.

The broken lines in the figures show portions of the animal cage which form no part of the claimed design. The animal cage is shown with a symbolic break in its length and width.

(Continued)

The appearance of any portion of the animal cage between the break lines form no part of the claimed design.
